(57) **CLAIM**

The ornamental design for a front face of a container, as shown and described.

DESCRIPTION

FIG. 1 is a perspective view of a front face of a container showing my design;

FIG. 2 is a front elevation view thereof;

FIG. 3 is a side elevation view thereof with the opposite side being a mirror image thereof;

FIG. 4 is a rear elevation view thereof; and,

FIG. 5 is a top plan view thereof.

The broken lines showing a portion of the container and brackets are for illustrative purposes only and form no part of the claimed design.

1 Claim, 4 Drawing Sheets
